UNITED STATES PATENT OFFICE.

CHARLES GEORGE MERIDETH, OF EVANSVILLE, INDIANA.

CONDUCTOR TERMINAL.

Application, filed June 30, 1927. Serial No. 202,544.

The present invention relates to conductor terminals, particularly those for connecting conductors to the posts of storage batteries such as are used for ignition, lighting, and starting purposes on automobiles and on radio batteries.

The objects of the invention are, first, the provision of an improved quick-attachable and detachable conductor terminal having novel means whereby it may be applied to, or removed from, the battery post or terminal without requiring the use of a tool; second, to provide an improved terminal clamp which will serve the double purpose of securing the conductor and clamping the terminal and conductor to the battery post; third, to provide a one-piece, preferably stamped, combined conductor and battery post gripping or clamping device, and a quick-acting hand operated element whereby the combined conductor terminal and battery post gripping member may be secured to, or released from, the battery post.

Other objects and characteristics of the invention will appear from the annexed specification, and the novel features and combinations of parts are set forth in the claims.

In the accompanying drawings:

Figure 1, is a plan view showing the invention clamped to a battery post;

Fig. 2, is a similar view, showing the device in open condition;

Fig. 3, is a horizontal section showing the device clamped on a battery post; and

Figs. 4 and 5, are opposite side elevations showing the device clamped on a battery post.

Any suitable conducting material is employed for those parts of the device requiring electrical contact with the end of the conductor and with the battery post.

One of the advantages of my invention is that it may be stamped out of sheet metal, such as copper, brass, or other suitable electrical conducting material, at small cost, as contrasted with those cast or solid metal conductor terminals which have heretofore been used; furthermore, the present clamping terminal requires no screws, nut, special wedges, or other heavy and relatively expensive parts and yet the terminal may be quickly and easily tightly clamped around the post, there to remain until released, by simple hand manipulation, without requiring the use of wrenches, screw drivers, pliers, or other special tools, thus enabling any person

to apply or remove the device when desired.

Another feature of the present invention is that the terminal is so constructed that the act of clamping it around the battery post, also clamps the terminal on the end of the conductor, thus doing away with special nipples, or other fittings which have been required solely to attach the terminal to the conductor, irrespective of the clamping means which may be used to secure the terminal to the battery post.

The conductor to which the terminal is applied is of any kind commonly used and is designated 1.

The battery post is shown at 2.

My improved terminal comprises but two elements, namely the terminal proper 3, and the cam lever 4 by which it is closed or allowed to open.

The terminal 3 is preferably made in a single piece, stamped from any suitable sheet metal of conducting properties. Being formed of sheet metal, there is a certain inherent resiliency which causes the terminal to open when the cam lever 4 is released, as shown in Fig. 2, so that it can be readily applied to, or removed from, the battery post 2.

The terminal has a band with a nearly complete substantially circular part 5 which is adapted to receive the battery post 2. One of the projecting plates or ends of the strap is shown at 6 and is provided with ears 7 between which is located the cam lever 4 which has any suitable pivotal connection 8 with said ears or lugs 7. The other end of the band 9 lies between the lugs 7 and is positioned to be forced by the cam lever 4 from the position shown in Fig. 2 to that appearing in Figs. 1 and 3 for the purpose of clamping the terminal on the post 2. When the cam lever 4 is swung to the position shown in Fig. 2, the inherent resiliency of the metal of the terminal causes the clamping band or strip to open.

The body of the terminal is in the form of a hollow bead 10 rising from, and being narrower than, the nearly circular part 5 of the clamping band or strip. This bead is preferably closed at its inner end 11 although it is not essential that this be so. The other end 12 is open to receive the end of the conductor 1. The inner face of the bead 10 is open so that the end of the conductor is exposed as shown at 13, Fig. 2, and this enables the conductor itself to come into direct

contact with the battery post 2 so that when the cam lever 4 is swung to the position shown in Figs. 1 and 3, not only is the terminal clamped around the battery post, but 5 the conductor is drawn tightly against the post so that good electrical contact is effected. When the terminal is clamped on the post 2 the gripping action is not only against the conductor end but certain parts 10 of the strap are in engagement with the post as shown at 14 and 15.

By reason of the partly circular form assumed by the conductor end, the cam action causes the conductor to be very tightly 15 gripped between the walls of the bead 10 and the battery post so that slippage from vibration or other causes is prevented.

What I claim is:

A conductor terminal comprising a contractile band of general circular shape having an arc-shaped hollow bead which is open at its inner face and is adapted to receive the end of the conductor and to hold said end in arc-shaped arrangement exposed for direct contact with a battery post or other terminal, said band being provided with overlapping end parts, and a cam lever carried by one of said ends and co-operating with the other end for the purpose of effecting clamping of the band and conductor end on the battery post.

In testimony whereof I affix my signature.

CHARLES GEORGE MERIDETH.
